MEANS FOR APPLYING WOUND COVERING
TO ELASTIC THREADAnton G. Seifried, Akron, Ohio, assignor to The
B. F. Goodrich Company, New York, N. Y., a
corporation of New YorkOriginal application December 12, 1946, Serial No.
715,881. Divided and this application April 8,
1950, Serial No. 154,779

2 Claims. (Cl. 57—15)

1

This invention relates to applying wound coverings about elastic thread and is especially useful in the application of windings of textile material about fine threads of elastic rubber or other rubber-like material.

The present application is a division of my application Ser. No. 715,881, filed December 12, 1946, entitled "Applying Wound Covering to Elastic Thread," now Patent No. 2,509,372 issued May 30, 1950.

In the manufacture of textile covered rubber thread it has been desirable to provide a stretchable covering of cotton, rayon, silk or similar textile threads wound helically about a fine filament of rubber or other elastic rubber-like material in layers of different angular pitch. A great many threads may simultaneously be covered under the care of a single operator and machines for such operations have usually been provided with a great number of fliers for handling a multiplicity of threads.

Heretofore difficulties have been experienced in simultaneously driving the fliers at uniform speeds especially in starting and stopping the fliers. Other difficulties have been encountered in stopping and starting individual fliers such as becomes necessary due to breaking of threads. Still further difficulty has been encountered due to change in diameter of the reels of covering material on the fliers causing change in the lay of the covering about the rubber thread.

It is an object of the invention to overcome the foregoing and other difficulties.

Other objects are to provide for positive driving of the fliers, to provide a single source of driving power for the supply, the fliers and the wind-up reels, to provide for driving the fliers first frictionally to substantially the normal velocity, to provide for selectively disconnecting the fliers from the source of power, and to provide for variable driving of the supply and the wind-up reels to provide uniform angular disposition of the covering upon the rubber thread.

These and other objects will appear from the following description and the accompanying drawings.

Of the drawings.

Fig. 1 is a front elevation of apparatus constructed in accordance with and embodying the invention.

Fig. 2 is a detail view of a portion of the wind-up mechanism.

Fig. 3 is a side elevation of the apparatus, as seen from the left in Fig. 1.

2

Fig. 4 is a side elevation of the apparatus as seen from the right of Fig. 1, parts being broken away.

Fig. 5 is a detail view of one of the fliers and its driving connections, parts being broken away and parts shown in section.

Referring to the drawings, these show apparatus for covering two rubber threads, it being understood that in production apparatus a multiplicity of threads may be covered by a single apparatus. A frame 10 has vertical frame members 11, 12, 13, 14 secured together by longitudinal rails 15, 16 on which similar geared transmission units 17, 18 are mounted in vertical alignment for driving the fliers 19, 19a.

Each geared transmission unit, as illustrated in Fig. 5, has a housing 20 in which a worm 21 of high pitch is mounted with its axis vertically supported on ball bearings 22. The worm has an axial bore which surrounds a hollow shaft 23 extending therethrough. A horizontal shaft 24 is also journaled in the housing and has a worm wheel 25 secured thereto and engaging the worm 21. The hollow shaft 23 has a collar 26 secured to it near its upper end by set screws 27. A flange 28 is fixed to collar 26 and has a pair of driving pins 29 secured thereto. A flange 30 is fixed to the worm 21 and has sockets 31 for receiving the tapered ends of the drive pins for positively driving the flange 28 from the worm 21.

A cheese 35 of covering material wound on a paper tube 36 is mounted about collar 26 against flange 28 and is held frictionally thereon by the collar. A second flange 37 rests on the upper end of the cheese and has a centering collar 38 thereon which fits within the upper end of the paper tube 36 and about shaft 23. An empty tube may be removed and replaced by a full tube by removing the flange 37. A guide bushing 40 has a frictional fit in the bore of shaft 23 and carries a guide disc 41. A flier arm 42 comprising a thin apertured disc 43 of vulcanized fiber for surrounding the guide bushing 40 and a wire arm 44 having a pigtail guide 48 at its outer end and fixed to the fiber disc, is frictionally held against the flange 37 by a weighted loose collar 45. This permits the arm to rotate relative to the cheese under light frictional drag during rotation of the cheese about the rubber thread.

The rubber thread 50 is drawn upwardly through the bore of the shaft 23 during the winding operation and the covering material 51 is unwound from the cheese 35 and is guided by the arm 42 and disc 41 as it is wound onto the rubber thread.

An important feature of the invention is in the provision of means for driving the flier frictionally until it attains the high speed of its driver and thereafter driving it positively.

For driving the flier frictionally, a clutch disc 52 is fixed to shaft 23 and is opposed to a clutch member 53 slidably mounted on the upper end of worm 21. Clutch member 53 has a friction face 54 and is retained on the worm by spring-pressed balls 55 engaging in dumb-bell shaped cavities 56 in the worm. A collar 57 is supported below the clutch member 53 and acts as a clutch shifter. Shaft 23 is formed at its lower end with a bulbed enlargement 58 whereby it may be engaged by a removable shifter 59.

When the shaft 23 is raised by the shifter 59, the driving pins 29 are raised from the sockets 31 and the clutch member 53 is contacted by the collar 57 and raised so that its retainer balls 55 engage the upper part of the dumb-bell depressions holding the flier at its disengaged position where the cheese tube may be removed and replaced by a loaded tube. As upward pressure of the shifter 59 is released, the clutch member 53 stays at its upper position, the clutch member 52 is pressed thereagainst by the weight of the cheese and the flier is frictionally driven. When the flier attains full speed, the shaft 23 is lowered by the shifter 59, thereby engaging the driving pins 29 with the disc 30, and driving the flier positively. A latch 60 is pivotally mounted on the housing 20 and may be manually engaged under the flange 28 to hold the flier in disengaged position while making the change. Fliers 19, 19a and their drivers 17, 18 are of the same construction except that the ratio of gearing may be different to apply successive coverings as different angular advance or lay and the fliers 19 and 19a are driven in opposite directions to lay coverings of crossed windings.

For feeding the rubber thread to the covering mechanism, a pair of cradle rolls 65, 66 are fixed to horizontal shafts 67, 68 respectively which extend across the lower part of the frame and are journaled thereon, there being one pair of cradle rolls beneath each flier 19. A roll 69 of rubber thread is placed on the cradle rolls and its thread 50 is led under a fixed guide bar 71 in vertical alignment with the axis of the flier 19. The cradle rolls are power-driven as hereinafter described.

For withdrawing the covered rubber thread from the flier 19a, a horizontally disposed power driven shaft 72 is journaled in the frame and has two grooved pulleys 73, 74 fixed thereto above each flier 19a, the pulley 73 being positioned with its groove in alignment with the axis of the flier. A shaft 75 is also journaled in the frame parallel to shaft 72 and is driven therefrom by sprockets 76, 77 engaging a chain 78. The covered thread is led about the large pulley 73, then about the shaft 75 and then about the small pulley 74 whereby enough friction is developed to pull the thread from the supply roll through the fliers.

A reel 80 for winding up the covered thread is removably mounted in chucks 81, 82 rotatably supported by the frame. One of the chucks 81 is driven by a chain 83 and sprockets 84, 85 from a shaft 86. Shaft 86 is in turn driven from shaft 72 by a gear 87 on shaft 72 engaging a gear 88 rotatable about a stub shaft 89 and a gear 90 fixed to gear 88 and engaging a gear

91 on shaft 86. Shaft 12 is driven in a manner hereinafter described.

For distributing the covered thread on the reel 80, a pair of vertically disposed shafts 95, 96 are journaled on the frame. Arms 97, 98 are fixed thereto respectively and their outer ends are pivotally connected to a transverse bar 99 having pigtailed 100 for guiding the threads. A crank pin 101 is fixed to sprocket 84 and a connecting rod 102 operated thereby is connected to an arm 103 fixed to shaft 95. The arrangement is such that the transverse bar is moved laterally to distribute the thread on the reel as the reel is rotated.

It is also a feature of the invention to drive all of the fliers, the supply rolls and the wind-up reels from a single source of power and thereby to provide uniform speed throughout. To this end, a motor 105 is provided on a platform extension 106 of the frame and a pair of variable speed transmission units 107, 108 are provided between the motor and the driven mechanism. The drive shafts 24 of the geared transmissions of fliers 19, 19a are connected to each other in series by flexible couplings 109 with a driving shaft 110 which is driven from motor 105 by a chain 111 and sprockets 112, 113. A second sprocket 114 on the shaft of motor 105 drives a sprocket 115 on the input shaft 116 of speed transmission 108 through a chain 117. The output shaft 116a of the transmission 108 carries gear 104 which meshes with a gear 104a on a shaft 118. Shaft 118 has a sprocket 119 secured thereto which drives a sprocket 120 on a shaft journaled on the frame through a chain 121. This arrangement provides for driving the fliers 19a in the opposite direction to the direction of flier 19. Sprocket 120 is connected to fliers 19a by a flexible coupling 122 and similar couplings connect the drive shafts of fliers 19a to each other to drive them in unison. The arrangement is such that by adjustment of the transmission 108 through hand wheel 123 thereon, the fliers 19a may be driven at a different speed with relation to fliers 19. This is desirable where the angular pitch of one layer of the covering is to be different than that of another layer. One adjustment of transmission 108 fixes the desired ratio which continues throughout a run of thread. A dial 161 on the transmission 108 indicates the setting thereof.

The second variable speed transmission 107 is employed to adjust the speed of travel of the rubber thread through the fliers. It is driven by a sprocket 124 fixed to shaft 116 and connected by a chain 125 to a sprocket 126 on the input shaft 127 of the transmission. Output shaft 128 is connected to a speed reducer 129 which has a sprocket 130 connected by a chain 131 to a sprocket 132 fixed to shaft 68 which drives the cradle rolls. Shaft 68 has a gear 135 fixed thereto which meshes with a gear 136 rotatable about a stub shaft 137. A sprocket 138 is fixed to gear 136 and engages a chain 139 which drives a sprocket 140 rotatably mounted on a stub shaft 141. A sprocket 142 is fixed to sprocket 140 and drives shaft 72 through a chain 143 engaging sprocket 76. The arrangement is such that the surface speed of cradle rolls 65, 66 and the pulling pulleys 73 is uniform and the rubber thread proceeds from one to the other with substantially no change of stretch, the speed of travel of the rubber thread being controlled by the variable speed transmission 107.

During the covering operation, the amount of covering material on the flier spools gradually decreases with a reduction in diameter of the material on the spools which would normally result in a change in the lay of the covering. The spools hold a considerable amount of covering ordinarily taking a run of eight hours to empty them. To provide constant compensation for such change in the lay is an important feature of the invention, and for this purpose a sprocket 150 is secured to a ratchet 150' which is fixed to the control shaft 151 of the variable transmission 107. An electric motor 152 is connected through a series of geared speed reducers 153, 154 to a sprocket 155 which engages a chain 156 meshing with sprocket 150. The arrangement is such that the speed of travel of the rubber thread through the fliers is gradually changed throughout the run from full spools on the flier to empty ones and the change in speed is such as to maintain the lay of the coverings at a desired angle. The variable speed transmission 107 is provided with a hand wheel 160 fixed to shaft 151 and sprocket 150 is secured to the shaft by a ratchet 150' permitting free turning in one direction so that the transmission can be adjusted at the end of a run to starting position.

The operation of the apparatus is as follows: The variable speed transmission 108 is set for the desired speed ratio of the fliers 19 and 19a. The transmission 107 is set at its starting position. Spools 69 of rubber thread are placed on the cradle rolls and the ends of the threads are threaded through the fliers and about the pulling rolls to the reels. A full spool of covering material has previously been placed on each flier, the spools all being filled to the same diameter. The ends of the covering material are tied to the rubber threads. The motors 105 and 152 are then started and no attention of the operator is required except to watch for broken threads. If a flier spool is to be stopped, the operator raises the shaft 23 by use of the shifter 59 and stops the flier long enough to tie in the thread. When a long delay is necessary the entire apparatus may be stopped by stopping the motors 105 and 152 and, due to the geared drive of the fliers, stopping and starting of the entire bank of fliers is accomplished simultaneously.

While the apparatus has been shown as one for covering two threads, in practice many threads are covered simultaneously by a single machine.

Where the term rubber thread is used in this description it is intended to include elastic threads of soft vulcanized rubber either natural or synthetic, or other materials having the physical characteristics of rubber.

Variations may be made without departing from the scope of the invention as it is defined by the following claims.

I claim:

- 5 1. Apparatus for simultaneously winding coverings about a plurality of elastic threads, said apparatus comprising an elastic thread supply, a plurality of fliers, wind-up means for drawing elastic thread from said supply through said fliers and rewinding it, positive driving means for supplying power at the same velocity to all said fliers, and clutch means at each flier on said driving means for engaging and disengaging the flier individually with said driving means, said clutch means comprising a friction clutch initially engageable with said flier to accelerate the velocity of the flier to normal speed, and a positively engageable clutch subsequently engageable with said flier at such normal speed to maintain
- 10 20 equal velocity of said fliers during continued operation.
2. Apparatus for simultaneously winding a covering about a plurality of elastic threads, said apparatus comprising a plurality of supply spools for storing elastic thread, a reel for drawing elastic threads from said supply spools, a plurality of fliers each rotatable about a reach of the elastic thread between said supply spools and said reel for applying a helical covering about
- 25 30 35 40 said threads, and means for driving said supply spools, said reel, and said fliers, said driving means comprising a single power supply for said fliers as a group and a geared driving connection thereon at each flier for driving said fliers positively in unison from said power supply, said fliers each having means for selectively disconnecting it from its driving connection, said selective disconnecting means comprising a positive drive clutch and a friction clutch engageable in advance of engagement of said positive drive clutch to accelerate the velocity of said flier in advance of engagement of said positive drive clutch.

ANTON G. SEIFRIED.
